UNITED STATES PATENT OFFICE.

FRANK C. RHEUBOTTOM, OF UNION CITY, MICHIGAN.

BINDING DEVICE.

1,048,098.

Specification of Letters Patent. Patented Dec. 24, 1912.

Application filed October 24, 1910. Serial No. 588,845.

To all whom it may concern:

Be it known that I, FRANK C. RHEUBOTTOM, a citizen of the United States, residing at Union City, in the county of Branch and State of Michigan, have invented a new and useful Binding Device, of which the following is a specification.

This invention relates to binding devices and more particularly to means whereby the 10 end portions of a chain may be adjustably connected and, at the same time, prevented from pulling apart.

With the foregoing and other objects in view which will appear as the description 15 proceeds, the invention resides in the combination and arrangement of parts and in the details of construction hereinafter described and claimed, it being understood that changes in the precise embodiment of 20 the invention herein disclosed can be made within the scope of what is claimed without departing from the spirit of the invention.

In the accompanying drawings, the preferred form of the invention has been shown.

In said drawings:—Figure 1 is a perspective view of the chain, the same being shown in position to support the arms of a corpse. Fig. 2 is a perspective view of the buckle 30 portion of the chain. Fig. 3 is a central longitudinal section through the buckle and through those portions of the chain engaging the same. Fig. 4 is a detail view of that end of the chain farthest removed 35 from the buckle.

Referring to the figures by characters of reference, 1 designates a chain, composed of a plurality of links 2 of the type shown in the drawings. A link, 3, at one end of the 40 chain is connected to a buckle 4, by separating the ends of the link, and passing them into an eye 5 in the buckle, as shown in Fig. 3, so as to engage a bar 6 on the buckle. Projections 7 and 8, extend from 45 the two ends of the buckle and constitute means about which the chain may be wound when not in use, thus forming a compact bundle or roll.

The end portion 10 of the buckle is provided with an opening 11, through which 50 the chain is passed, there being an inclined

tongue 12 struck up from the buckle and adapted to engage the bulged portions 13 of the links so as to hold the chain in adjusted positions, as shown in Fig. 3. The 55 end link 14 of the chain is distorted to form an enlarged loop 15 which prevents the chain from being drawn out of the opening.

It is to be understood that the device 60 herein described can be used for various purposes. Should it be desired, for example, to apply the device to a corpse, the chain is slipped around the arms, at points just above the elbows, and with the buckle 65 over the left side. The loose end of the chain is then pulled to bring one of the links into engagement with tongue 12 as shown in Fig. 3. To adjust the chain the buckle is lifted to an angle by pulling the 70 end 14 of the chain, and the chain will slide in either direction through the opening in the buckle to tighten or to loosen it.

What is claimed is:—

As an article of manufacture, a binding 75 device, including a chain made up of cut links each having a bulged end portion, a plate having spaced openings adjacent the respective ends thereof, a tongue struck from the plate to form one of the openings, 80 said tongue being flat and inclined upwardly relative to the plate and overhanging the opening formed thereunder, one end portion of the chain being mounted to slide in one direction under the tongue and 85 through the opening thereunder, said tongue coöperating with the bulged end portion on any link of the chain to hold the chain against withdrawal through the opening, means engaging the other of said openings 90 for connecting the other end of the chain to the plate, and parallel projections upon the ends of the plate, those portions of the chain engaging the plate being extended between 95 the projections.

In testimony that I claim the foregoing as my own, I have hereto affixed my signature in the presence of two witnesses.

FRANK C. RHEUBOTTOM.
